CLAIM

We claim the ornamental design for a mantle for a lantern, as shown and described.

DESCRIPTION

FIG. 1 is a perspective view of a mantle for a lantern showing our new design;

FIG. 2 is a front elevation view thereof, the rear, left, and right elevation views being a mirror image thereof;

FIG. 3 is a top plan view thereof; and,

FIG. 4 is a bottom plan view thereof.

Broken lines and the area within the broken lines are for illustrative purposes only and form no part of the claimed design.

Oblique line shading is used to illustrate transparency.
